UNITED STATES PATENT OFFICE.

JACOB MORRIS FRANKLIN, OF BROOKLYN, NEW YORK, ASSIGNOR OF ONE-THIRD TO
EMANUEL DEITZ AND ONE-THIRD TO ABRAHAM DEITZ, BOTH OF NEW YORK, N. Y.

GARMENT-POCKET.

1,397,729.

Specification of Letters Patent.

Patented Nov. 22, 1921.

Application filed September 12, 1919. Serial No. 323,294.

To all whom it may concern:

Be it known that I, JACOB MORRIS FRANKLIN, a citizen of the United States, residing in the borough of Brooklyn, county of 5 Kings, and State of New York, have invented certain new and useful Improvements in Garment-Pockets, of which the following is a specification.

My invention relates to pockets for garments and relates particularly to pocket constructions having more than one compartment, and in which one of these compartments is provided with means for providing a maximum of security against loss or theft 10 of the contents of this compartment, while another of the pocket compartments is more readily accessible. An object of my invention, in garment pockets having two receptacle parts or compartments, is to provide a 15 pocket construction in which double security is provided for one of the pocket compartments, while the other pocket compartment may either be left freely open or secured as may be desired. My invention includes features of construction and combinations of 20 parts as will appear from the following description. I shall now describe the garment pocket construction embodying my invention illustrated in the accompanying drawings and shall thereafter point out my invention in claims.

Figure 1 is an outside elevation showing the pocket construction with the parts in the position in which double security is provided for an inner compartment while an outer pocket compartment is left freely open and readily accessible.

Fig. 2 is a central longitudinal section on a vertical plane indicated by the line 2—2 40 of Fig. 1 as viewed from the left.

Fig. 3 is a similar view with the pocket parts in disengaged position for thereby permitting access to the inner pocket compartment as well as to the outer pocket compartment.

Fig. 4 is a transverse section on a horizontal plane indicated by the line 4—4 of Fig. 2 as viewed from above.

In the pocket construction embodying my invention illustrated in the accompanying drawings, there is an upper part 1 of the garment, and a lower part 2 thereof, between which there is provided a usual pocket slit, these garment parts 1 and 2 50 being of the same piece of cloth and extend-

ing around the edge of the pocket slit at the sides of the pocket as appears in Fig. 1 of the drawings. Below the pocket slit and at the inner side of the lower garment part 2 there are provided three pocket walls comprising an outer pocket wall 3, an inner pocket wall 4 and an intermediate pocket wall or partition 5. These three pocket walls are of the same extent or dimensions at the bottom and sides of the pocket and at 60 their margins around the bottom and sides are stitched together, as shown in the drawings, so as to form an outer pocket compartment A and an inner pocket compartment B. The inner pocket wall 4, which is 65 at the back or inside, extends up and is attached at its upper marginal edge to the upper garment part 1 above the pocket slit, the outer pocket wall 3 at its upper end terminates at the pocket slit, while the intermediate partition pocket wall 5 in its upward extension terminates a considerable distance below the pocket slit and below the upper end of the outer pocket wall 3, so 70 that thereby the inner pocket compartment 75 B is of less depth than the outer compartment A.

A pocket flap 6, shown as formed of two thicknesses of material, extends from the upper margin of the inner pocket wall 4 85 and adjacent garment material 1 above the pocket slit, and is of a length adapting it to overlap upon the intermediate pocket partition wall 5 at the inner side of the outer pocket wall 3, as shown in Figs. 1 and 2. 90 Also, if desired, this flap 6 may be placed at the outer side of the outer pocket wall 3, as shown in Fig. 3, so as then to overlap correspondingly, but of course to a greater extent corresponding substantially to its full 95 length, upon the outside of the outer pocket wall 3. The upper margin of the intermediate or partition wall 5 is provided with a button-hole 7 and at the correct location the inner pocket wall 4 has secured thereon 100 at the inside of the pocket compartment B a button 8 co-operative with the button-hole 7 in the partition wall 5 for thereby closing and providing a measure of security for the inner pocket compartment B. Another similar button 9 is secured at the outside of the outer pocket wall 3 opposite to or in alignment with the inner button 8, so that this button 9 projects from the outside of the outer pocket wall 3 and from the outer side 110

of the lower garment part 2 which overlies the outer pocket wall 3, and which at this point may be considered as forming virtually a part thereof, as is shown in the 5 drawings. The pocket flap 6, which is shown as of tapered form, is provided in the margin thereof at the middle with a button hole 10 which is adapted to be coöperative with either of the buttons 8 or 9, according to the position which it is desired 10 that the protective flap 6 shall occupy.

In Figs. 1 and 2 the position of the pocket parts is such that a maximum degree of or 15 double security is provided for the inner pocket compartment B, while the outer pocket compartment A is freely open and readily accessible. In this position of the parts of the pocket illustrated in Figs. 1 and 2, the button-hole 7 in the margin of the 20 partition wall 5 is buttoned over the inner button 8, and also the flap 6 is in an inner position in which it extends down at the inner side of the outer pocket wall 3 into overlapping relation at the outer side of the 25 partition wall 5, and has its button-hole 10 buttoned over the inner button 8 at the outer side of the upper margin of the partition wall 5, thereby affording a double measure 30 of security for the inner pocket compartment B while the outer pocket compartment A is left freely open at the upper end of the outer pocket wall 3, as shown in Figs. 1 and 2. In this position of the pocket parts valuable papers, money, or other articles which 35 it is desired to protect against loss or theft may be carried in the inner pocket compartment B, while the outer pocket compartment A may contain anything which it is desired shall be readily accessible and which there 40 is no particular need to protect, such for example, as a pocket handkerchief. In the position of the pocket parts illustrated in Figs. 3 and 4, the flap 6 has been unbuttoned from the inner button 8 and pulled to 45 the outer side of the garment beyond the outer pocket wall 3 and lower garment part 2, and also as shown in these figures, the partition wall 5 has been unbuttoned from the inner button 8 so as thereby to give access 50 to both of the pocket compartments A and B.

If desired, referring now more particularly to Figs. 1 and 2, the pocket flap 6 may be unbuttoned from the inner button 8, leaving the partition wall 5 still buttoned over 55 this button, and the flap 6 may then have its button-hole 10 engaged with the outer button 9. In this position of the parts, not particularly illustrated in the drawings, but readily understood therefrom, it will be evident 60 that a double measure of security is still provided for the inner pocket compartment B, while the outer pocket compartment A, instead of being freely open as illustrated in Figs. 1 and 2, then will be protected by

the overlying flap 6. In this position of the 65 pocket parts access to the outer compartment A cannot be had without first unbuttoning the flap 6 from the outer button 10, and access to the inner compartment B cannot be had without also unbuttoning the partition wall 5 from the inner button 8, as will be readily understood.

A further, and what may be called a third measure of security, is provided for the inner pocket compartment B by reason of the 70 fact, particularly in the closed position thereof, that there is no reason for suspecting the existence of this inner pocket compartment B, nor is there any outward signs of it nor any readily ascertainable means of 75 discovering it, so that unwarranted access at most is never likely to be obtained to more than the outer pocket compartment A.

It is to be understood that the pocket construction of my invention may be applied to 80 or embodied in any garment in any position thereon or part thereof, or in any article of apparel. However, the pocket construction of my invention is considered to be particularly adapted for use as the hip pocket of 85 trousers, although as above noted, not in any wise limited to this particular use.

It is obvious that various modifications may be made in the construction shown in the drawings and above particularly described within the principle and scope of 90 my invention.

I claim:

A pocket construction for a garment having a slit formed therein, comprising inner 100 and outer walls attached at margins thereof to the garment adjacent the slit therein, a partition wall having its margin attached to said inner and outer walls, said partition wall being disposed intermediate said inner 105 and outer walls and forming therewith inner and outer pocket compartments, a flap on the inner wall adapted to extend over the edge of the intermediate wall at the inside of the outer wall and also adapted to extend 110 over the exposed edge of the outer wall to the outside thereof so as to occupy either an inner or an outer position as may be desired, the margin of the intermediate wall having a button-hole therein, a button on the 115 inner wall coöperative with said button-hole to close the inner compartment, and a button on the outside of the outer pocket wall, the margin of said flap being provided with a button-hole coöperative with the one or the 120 other of said buttons according to whether the flap is in its inner or its outer position and whereby in either case double security will be provided for the inner pocket compartment.

In testimony whereof, I have affixed my signature to this specification.

JACOB MORRIS FRANKLIN.
